[57] CLAIM

The ornamental design for a motor home body front panel exterior surface, as shown and described.

DESCRIPTION

FIG. 1 is a left side elevational view of a motor home body front panel exterior surface showing our new design, it being understood that the broken lines are for illustrative purposes only and form no part of the claimed design;

FIG. 2 is a perspective view thereof;

FIG. 3 is a front, elevational view thereof.

FIG-1

FIG-2

FIG-3
